CONTROL SYSTEM FOR VARIABLE-SPEED
ALTERNATING-CURRENT MOTORS

Kurt Mahnke, Forest Hills, and James W. York,
Irwin, Pa., assignors to Westinghouse Electric
Corporation, East Pittsburgh, Pa., a corpora-
tion of Pennsylvania

Application December 13, 1946, Serial No. 716,030

9 Claims. (Cl. 318—262)

1

Our invention relates to electric systems for controlling alternating-current multi-speed motors of the type in which several field windings and appertaining terminal groups are provided for producing different respective numbers of field poles, in order to permit a selective operation of the motor at respectively different speeds depending upon which terminal group is energized at a time.

Such control systems, in general, are known, for instance, from United States Patent 2,393,998 of Kurt Mahnke, assigned to the assignee of our invention; and our invention, in some of its aspects, may be considered to involve improvements over systems according to the patent as regards circuit design and speed transfer performance of the control system.

It is among the objects of our invention to provide a proper timing of the accelerating or decelerating performance of an alternating-current multi-speed motor with the aid of timing relays of simpler design than those required in the known system. That is, in the known system the timing relays for determining the minimum period of time, which has to expire between the energization of one motor terminal group and the subsequent energization of the next terminal group for a higher or lower motor speed, had to be designed in such a manner that they operated with a delayed pick-up performance as well as with a delayed drop-out performance in order to render their timing function effective both when accelerating and when decelerating the motor. The invention, according to the just-mentioned object, aims to permit the use of relays which are capable of timing the speed transfer for acceleration as well as for deceleration, although they have a substantially instantaneous pick-up performance and only a delay drop-out performance. Such relays may consist, for instance, of the customary direct-current relays with a short-circuited winding on the magnet core of the relay. It thus becomes possible to equip the control system with these simple relays of customary type with the advantage of a considerable simplification of the system, reduced space requirements for the relays, and reduced cost of the relay equipment.

Another object of our invention concerns itself with the provision of a load-responsive relay in the motor control system in order to prevent the motor from operating at high speed when the load current flowing through the motor at that speed exceeds a safe limit value. In the known system containing such a load relay, this relay

2

may prolong the time needed for accelerating the motor to its maximum speed. The last-mentioned object, therefore, aims at designing a motor control system in such a manner that the protective load-responsive relay does not interfere with a quick adjustment of the motor to high or highest speed but comes into effect only when thereafter the load current persists unduly long at a value above the safe limit.

10 A further object of the invention relates to motor control systems for hoists and aims at the provision of a motor control system for alternating-current multi-speed motors in which a load-responsive relay of the kind just mentioned is so controlled that its control effect occurs only when the motor is operated in the hoisting or heave-in direction but is eliminated or suppressed during lowering or pay-out performance.

These and more specific objects of the invention, as well as the means provided by the invention for achieving these objects, will be understood from the following description of the embodiments illustrated in the drawings, in which:

Figures 1 and 2 represent two modifications 20 of a hoist control system designed in accordance with the invention and suitable especially for the control of hoisting equipment, such as marine winches.

In Fig. 1, the cable drum of a hoist or winch 25 is denoted by D. The drum is driven from an alternating-current motor M of the squirrel-cage type, preferably through the customary reduction gears (not illustrated). The drum is equipped with a friction brake B, which is electrically connected to the motor control system so that the brake is automatically set whenever the motor M is deenergized. The design and control of the brake B is not a part of the invention proper and may correspond to known constructions, for instance, as shown in the above-mentioned patent. Therefore, details of the brake and the appertaining control connections are not illustrated and further described in this disclosure.

The motor M is of the squirrel-cage type. It 30 has four groups of terminals T1, T2, T3 and T4. The motor field windings (not shown) attached to these terminals are so wound and arranged that the motor operates with 32 field poles for slowest motor speed when the terminals T1 are 35 energized, while the winding connections appertaining to the terminals T2 produce 16 field poles and hence, when energized, cause the motor to operate at twice the above-mentioned speed (second speed), the terminal group T3 energizes the 40 motor field for 8 poles in order to operate the 45

motor at four times the minimum speed (third speed); and the terminal group T4 is attached to field windings for 4-pole operation to operate the motor at maximum speed (fourth speed), which is eight times as high as the minimum speed. The terminal groups are energized, one at a time and in sequential order, from line terminals L1, L2 and L3 through a main switch S which remains closed during the performance of the system. The connection between the line terminals and the motor terminals is controlled by the contacts 1 and 2 of a hoist contactor H whose control coil is denoted by 3, and by the contacts 4 and 5 of a lowering contactor L whose control coil is denoted by 6. The function of contactors H and L is to reverse the phase sequence of the energizing voltage in order to permit operating the motor in the hoist or lowering (heave-in or pay-out) directions. The contactors H and L are so controlled that only one of them can close its contacts at a time.

The selection of the motor terminal group to be energized at a time is effected by means of speed control contactors denoted by 1M, 2M, 3M and 4M, respectively. Contactor 1M has a main contact device, which includes contacts 7, 8 and 9, for connecting the terminal group T1 to the line terminals. Contactor 1M has also two interlock contacts 10, 11 and a control coil 12. The contactor 2M has two contacts 13, 14 for shorting the terminal group T1 when the main contacts 15, 16 and 17 of the contactor are closed for connection of terminal group T2 to the line terminal. These contacts, together with an interlock contact 18, are controlled by a coil 19. The contactor 3M has main contacts 20, 21 and 22 which, when closed, connect the motor terminals T3 to the line terminals, contacts 23 and 24 of contactor 3M for short-circuiting the terminal group T4 when the main contacts are closed, and two interlock contacts 25 and 26, all contacts of contactor 3M being controlled by a coil 27. Contactor 4M has main contacts 28, 29, 30 and an interlock contact 31 controlled by a coil 32. Contacts 28, 29 and 30, when closed, connect the motor terminals T4 to the line terminals.

The above-mentioned contactors form part of a control system whose primary control device consists of a master controller C, here exemplified as being of the drum type and illustrated in developed form. The master controller has a group of contact fingers, such as those denoted by 41, for engagement by groups of contact segments denoted by 42, 43, 44 and 45. The controller is shown in its "off" position. It has 4 lowering positions and 4 hoisting positions for operating the motor in either direction at the 4 different speeds above mentioned. An emergency switch 46 is disposed close to the master controller, so that it can be operated by the attendant at any time during the actuation of the controller. The emergency switch 46 may consist of a thumb contact in the handle for turning the contact drum of the master controller. The system is energized through the emergency switch 46 and becomes deenergized to stop the motor when the switch 46 is opened.

The excitation of the control system is further dependent upon the operation of a low-voltage relay V whose coil 47 maintains its relay contacts 48 and 49 in closed position as long as the master controller is turned away from its "off" position. Upon occurrence of voltage failure at the line terminals, however, the relay V will drop

out and then also deenergize the control system and stop the motor. Thereafter the relay V will pick up only when the master controller is first turned back to the "off" position.

5 The control system is equipped with two control relays 3CR and 4CR in conjunction with respective timing relays 2T and 3T. This group of relays serves to secure a proper timing during accelerating and decelerating performance so that each following terminal group becomes energized only after the preceding terminal group has been energized a given period of time, thus limiting transitory overloads and securing a smooth speed transfer regardless of the speed at 10 which the master controller is moved from one to the next position. The control relay 3CR has three contacts 50, 51 and 52 controlled by a coil 53 whose circuit extends through the normally closed contact 54 of the timing relay 2T. The coil 55 of relay 2T is connected to the output terminals of a rectifier 57 and the relay magnet coil is equipped with a short-circuited winding 58 so that after deenergization of coil 55, the relay will drop out only upon the elapse of a time 15 interval, for instance, of about three-quarters second. The control relay 4CR has three contacts 58, 59 and 60 controlled by a coil 61 whose circuit extends through the contact 62 of timing relay 3T. Relay 3T has a main coil 63 connected 20 to a rectifier 64 and a short-circuited coil 65 to operate with a delayed drop-out. The timing period of relay 3T is preferably somewhat shorter than that of relay 2T, for instance, approximately half a second.

35 A load-responsive relay LR, with a contact 66 and a coil 67, is so arranged that the coil 67 is traversed by motor current when the terminal group T3 is energized. The coil 67 will then open the contact 66 if the motor current at the third speed exceeds a given value. This has the effect of preventing a transfer of the motor to the highest motor speed as long as the overload current persists.

40 The system, as a whole, operates in the following manner.

When the master controller C is in the illustrated "off" position, the closing of switches S and 46 has the effect of energizing the voltage relay V in the circuit:

50 L2-71-47-45-46-L3 (1)

55 Contacts 48 and 49 close and contact 49 bypasses the reset segment 45 of the master controller so that the relay V remains picked up if thereafter the master controller is turned away from its "off" position. The contact 48 connects the lead 70 with line terminal L3 and thereby energizes the coil 12 of contactor 1M in the circuit:

L2-71-18-31-12-44-50-70-48-49-46-L3 (2)

60 Contactor 1M picks up and prepares at contacts 7, 8 and 9 an energizing circuit for motor terminals T1. This circuit, however, remains open as long as neither contactor H nor L is energized. 65 The contact 10 of contactor 1M closes an energizing circuit for coil 55 of relay 2T; and coil 63 of relay 3T is also energized through the contact 25 of contactor 3M. Consequently, the two timing relays 2T and 3T pick up. Relay 2T opens its contact 54 and relay 3T opens its break contact and closes its make contact.

If now the master controller C is turned from "off" to first point hoist, the contactor H is energized in the circuit:

70 L2-71-3-41-42-48-49-46-L3 (3)

and closes its contacts 1 and 2, thereby energizing the motor M for operation at slowest (first) speed in the hoisting or heave-in direction. Contacts 1 and 2 also energize the coil 75 thus releasing the brake B.

When the master controller is turned to second point hoist, contactor 1M drops out because its coil circuit (2) is interrupted in the master controller at segment group 44. Interlock contact 11 of contactor 1M now closes and completes for coil 19 of contact 2M, the circuit:

L2-71-11-19-44-50-70-48-49-46-L3 (4)

The motor is now energized at terminals T2 for second speed. The interlock contact 10 of contactor 1M opens and deenergizes coil 55 so that timing relay 2T drops out and closes its contact 54, after elapse of its timing period of about three-quarters second.

When the master controller is advanced to third point hoist and after the relay 2T has dropped out, coil 53 of control relay 3CR becomes energized in circuit:

L2-71-53-54-42-48-49-46-L3 (5)

Contact 50 of relay 3CR now interrupts the coil circuit (4) of contactor 2M so that the terminal group T2 becomes disconnected, while contact 51 of relay 3CR closes for coil 127 of contactor 3M the circuit:

L2-71-18-31-27-59-51-70-48-49-46-L3 (6)

Contactor 3M picks up and connects motor terminals T3 to the line for third motor speed. The interlock contact 25 of contactor 3M deenergizes the coil 63 so that the timing relay 3T drops out upon elapse of its timing interval and then prepares a circuit for the coil 61 of relay 4CR.

When the master controller is advanced to the fourth point hoist and assuming that the relay 3T was given sufficient time to drop out, the control relay 4CR becomes energized in circuit:

L2-71-61-62-72-66-73-41-42-48-49-46-L3 (7)

Contact 60 of relay 4CR closes and thereby completes a self-holding circuit in parallel to the timing relay contact 62. Consequently, relay 4CR will remain picked up as long as the master controller remains in the fourth position hoist even if the timing relay 3T is subsequently caused to reopen its break contact at 62. Interlock contact 59 of relay 4CR interrupts the coil circuit (6) of contactor 3M so that terminals T3 become deenergized. Contact 58 of relay 4CR closes for coil 32 of contactor 4M the circuit:

L2-71-26-11-32-58-70-48-49-46-L3 (8)

Contactor 4M connects the terminals T4 to the line terminals for operating the motor at maximum speed.

Interlock contact 31 of contactor 4M then opens the coil circuit (6) of contactor 3M. Contactor 3M drops out and, by closing its interlock contact 25, reenergizes the rectifier 64 so that timing relay 3T picks up and opens its brake contact at 62. This, as explained above, is now without effect on relay 4CR and contactor 4M because relay 4CR remains sealed in at contact 60 as long as the master controller is kept on fourth position hoist. In this manner, the timing relay 3T is reset for a subsequent timing operation to take place when the master controller is turned back for deceleration of the motor.

It will be recognized from the foregoing that when the master controller is progressively ad-

vanced from the "off" position to the fourth point hoist, the timing relays 2T and 3T by virtue of their delayed drop-out performance determine the minimum interval of time that elapses between the initial energization of terminals T2 and that of terminals T3, and between the moments of initial energization of terminal groups T3 and T4. Consequently, when the master controller is moved quickly from "off" to fourth point hoist, the accelerating performance remains properly controlled by the timing relays and the associated other relay circuits. For instance, when the master controller is rapidly moved from "off" to fourth point hoist, contactor H picks up, contactor 1M drops out and contactor 2M connects the motor for second speed. The interlock contact 10 then deenergizes the timing relay 2T, so that this timing relay drops out after about three-quarters second and then energizes the control relay 3CR. This relay then energizes the contactor 3M for third speed and the interlock contact 25 deenergizes the timing relay 3T. After one-half second, relay 3T drops out and energizes relay 4CR which, in turn, trips the contactor 3M and picks up the contactor 4M for highest motor speed. With this performance the motor is caused to run first three-quarters second at second speed and thereafter one-half second at third speed before it is permitted to assume maximum speed.

When the master controller is suddenly moved from fourth point hoist to first point hoist, the first action of the control system is to interrupt the coil circuit of relay 4CR. This relay deenergizes contactor 4M and energizes the contactor 3M, thus transferring the motor from fourth speed to third speed. As the contactor 3M picks up, the time relay 3T is deenergized and drops out after elapse of its timing period of half a second. Then the contact 62 interrupts the coil circuit of relay 3CR. Relay 3CR, at contact 51, opens the coil circuit of contactor 3M and energizes, at contact 50, the coil 12 of contactor 1M. As a result, the motor is transferred from third speed immediately to first speed, and then continues running at lowest speed.

When the master controller is suddenly moved from fourth point hoist to "off," all contactors drop out and the motor is brought to a stop.

The operation of the system in the lowering direction is similar to the above-described hoisting operations, except that the contactor L closes instead of the contactor H, causing the winch motor to run in the opposite direction.

In the event that the current in the load relay LR exceeds a predetermined value when the motor is running at third speed hoist, the contact 66 opens and prevents relay 4CR from transferring the motor from third to fourth speed. When loads are hoisted that are in excess of a given load, for instance somewhat above one-half rated maximum load, the motor will not come up to fourth speed. However, when the motor is operated in the lowering direction, the contacts 66 of the load relay LR is bypassed in the master controller so that the system permits high speed lowering of all loads.

Reverting to the above-described functioning of the timing relays 2T and 3T, it will now be observed that the timing performance of these relays or either of them comes into effect not only during acceleration but also during deceleration of the motor and that the associated control circuits are so designed that in either case the delayed drop-out performance of the timing

relays determines the maximum speed of transfer.

The embodiment of a motor control system for a marine winch shown in Fig. 2 is largely similar to that of Fig. 1 with the exception of the system elements specifically described hereinafter. In order to make the similarities apparent and to obviate the necessity of again describing them in detail, the contactors, relays, motor, brake, winch drum, and master controller in Fig. 2 are denoted by the same unit characters as the corresponding system elements in Fig. 1, namely, by H, L, 1M, 2M, 3M, 4M, V, LR, 2T, 3CR, 3T, 4CR, M, B, D and C. For the same reasons, the individual parts of these devices are designated in Fig. 2 by the same reference numerals as in Fig. 1, except that in Fig. 2 the prefix 1 or 10 has been added. For instance, the contacts 101, 102 in Fig. 2 correspond to the contacts 1, 2 in Fig. 1; and the contacts 113, 114 in Fig. 2 correspond to the contacts 13, 14 in Fig. 1.

The differences of the system shown in Fig. 2 as compared with the system of Fig. 1 are essentially as follows.

The hoist contactor H in Fig. 2 is provided with an additional interlock contact 81, the lowering contactor L with additional interlock contacts 82, 83 and the relay 3CR with an additional interlock contact 84. The function of these interlock contacts is to provide electric interlocking aside from the interlocking occurring in the master controller.

In further distinction from the system of Fig. 1, the timing relays shown in Fig. 2 are illustrated as being connected to a suitable source of direct current which is represented merely by its positive and negative terminals marked $\oplus$ and $\ominus$, respectively. It will also be noted that the master controller C in Fig. 2 is not equipped with a contact segment for bypassing the contact 166 of the load-responsive relay LR. Consequently, this relay is capable of performing its protective function during hoisting, as well as during lowering performances of the system.

The above-mentioned differences are of minor nature, and they do not essentially alter the performance of the system. Therefore, the operation of the system when the master controller is moved, for instance from the "off" position, to first, second and third points hoist is essentially in accordance with the above-given description of the corresponding operating sequence for the system of Fig. 1. That is, the foregoing description of the sequential occurrence of the circuits (1) through (6) is substantially applicable to the system of Fig. 2, provided the analogous reference numerals of Fig. 2 and the above-mentioned additional interlock contacts are considered. However, the system shown in Fig. 2 is also characterized by more essential differences over the system of Fig. 1, and these differences account for a modified performance when the master control is moved from third to fourth position hoist or lower, as will be explained presently.

In the system of Fig. 2, the coil 167 of the load-responsive relay LR is so connected in the energizing circuit of motor M that the coil is traversed by load current only when the terminal group T4 of the motor is energized by the contactor 4M. As a result, the relay LR cannot interfere with the transfer of the motor from third to fourth speed but becomes effective only after the motor has been switched over to maximum speed and only when at that time an excessive load condition exists. Associated in functional respects with

the load relay LR is a timing relay 1T with a main coil 87, a short-circuited coil 88 and a contact 89, and also a control relay 5CR with two contacts 90, 91 and a control coil 92. Due to the just-mentioned connection of coil 167 in relay LR, and due to the operation of the additional relays 1T and 5CR, the control system operates in the following manner when the master controller is moved, from third to the fourth position, for instance, in the hoisting direction.

Relay 4CR picks up because its coil 161 becomes energized in the circuit:

L2-171-161-162-90-142-148-149-146-L3 (7a)

Contact 158 of relay 4CR closes for coil 132 of contactor 4M the circuit:

L2-171-111-126-132-158-170-148-149-146-L3 (8a)

Contactor 4M now connects motor M for operation at fourth speed, while contactor 3M drops out because its coil circuit, analogous to circuit (6), is opened at contact 131 of contactor 4M. Timing relay 1T, previously energized, drops out

after elapse of its timing period because the circuit of its coil 87 is interrupted at contact 86 of relay 4CR. When at that moment the load current of motor M is below the safe limit, relay LR remains dropped out with contact 166 open, and nothing further happens. When, however, the load current is excessive, so that relay LR is picked up and contact 166 closed when time relay 1T closes its contact 89, the following circuit is completed for coil 92 of relay 5CR:

L2-171-92-89-166-142-148-149-146-L3 (9)

Relay 5CR picks up and, at contact 90, opens the coil circuit (7a) of relay 4CR while sealing itself in at contact 91. Relay 4CR when dropping out, opens at contact 158 the coil circuit (8a) of contact 4M and closes, at contact 159, the circuit of coil 127 so that contactor 3M picks up. Thus, the motor M is automatically transferred back to third speed. When thereafter the load current of motor M drops to a permissible value, the contactor 4M can be made to pick up again for

operating the motor at maximum speed by turning the master controller C first back to third position hoist. This opens the holding circuit of relay 5CR and returns the system into the condition obtaining when the master controller C is moved from second to third point hoist. Then, the return of the master controller C to fourth point hoist will cause the contactor 4M to pick up.

The timing period of relay 1T is so chosen that it exceeds the duration of the load peaks normally occurring when the motor is transferred from third to fourth speed. Consequently, if these load peaks should temporarily cause the relay LR to pick up while the timing relay 1T holds its contact 89 open, the temporary closing of the load relay contact 166 is of no effect on the coil circuit (9) of relay 5CR so that the motor M is kept running at maximum speed.

It will be understood by those skilled in the art that control systems according to the invention can be altered and modified in various respects without departing from the essence of the invention and within the scope of the essential features of the invention, as set forth in the claims annexed hereto.

We claim as our invention:

1. A motor control system, comprising a multi-speed alternating-current motor having a plurality of selectively energizable field terminal

groups for correspondingly different operating speeds, circuit means for supplying energy to said motor, reversing contactor means disposed between said circuit means and said terminal groups for selectively controlling said motor to run in hoisting and lowering directions respectively, a plurality of speed-controlling contactor means disposed between said reversing contactor means and said terminal groups for selectively connecting said respective terminal groups to said circuit means, motor control means having selective contact devices and being operator-adjustable between an "off" setting and a plurality of "hoist" settings and a plurality of "lower" settings, said master controller being connected with said reversing contactor means and said speed-controlling contactor means for sequentially operating said speed-controlling contactor means for either selection of said reversing contactor means, a load-responsive relay having a coil connected between said reversing contactor means and one of said terminal groups for a given lower speed so as to be responsive to motor current flowing when said latter terminal group is energized and having a contact connected to the speed-controlling contactor means for the next higher speed so as to prevent said latter contactor means to energize said motor for said higher speed when said current exceeds a given maximum value, said master control means being connected with said contact so as to render it inoperative when said master control means are set for lowering operation.

2. A motor control system, comprising a multispeed alternating-current motor having a plurality of selectively energizable field terminal groups for correspondingly different operating speeds, circuit means for supplying energy to said motor, reversing contactors having respective contact devices series-disposed between said circuit means and said terminal groups for selectively controlling said motor to run in hoisting and lowering directions respectively, a plurality of speed-controlling contactors having respective contact devices series-disposed between said contactors and said terminal groups for selectively connecting said respective terminal groups to said circuit means, an operator-adjustable master controller having a plurality of selective "hoist" positions and a plurality of selective "lower" positions, all of said contactors having respective control coils connected with said master controller so that said speed-controlling contactors are sequentially operated together with either reversing contactor when said master controller is progressively adjusted through said "hoist" and "lower" positions respectively, a load-responsive relay having a coil circuit connected between said contact devices of said reversing contactors and the terminal group for second highest motor speed and having a break contact series-connected between said master controller and the coil of the speed-controlling contactor for highest motor speed so as to prevent said latter contactor from energizing said motor for highest speed when the motor current flowing at the second highest speed exceeds a given value, said master controller having contact means disposed to short-circuit said break contact when said master controller is in "lower" positions.

3. A motor control system, comprising a multi-speed alternating-current motor having a plurality of selectively energizable field terminal groups for correspondingly different operating speeds, circuit means for supplying energy to said motor,

reversing contactor means disposed between said circuit means and said terminal groups for selectively controlling said motor to run in hoisting and lowering directions respectively, a plurality of speed-controlling contactor means disposed between said reversing contactor means and said terminal groups for selectively connecting said respective terminal groups to said circuit means, master control means having selective contact devices and being operator-adjustable between an "off" setting and a plurality of "hoist" settings and a plurality of "lower" settings, said master controller being connected with said reversing contactor means and said speed-controlling contactor means for sequentially operating said speed-controlling contactor means for either selection of said reversing contactor means, a load-responsive relay having a coil connected between said reversing contactor means and one of said terminal groups for a given lower speed so as to be responsive to motor current flowing when said latter terminal group is energized and having contact means connected to the speed-controlling contactor means for the next higher speed so as to prevent said latter contactor means to energize said motor for said higher speed when said current exceeds a given maximum value, and circuit means connected with said relay and controlled in dependence upon the selected condition of said master controller so as to render said relay effective as regards the load-responsive control when said master control means are in "hoist" condition and ineffective when said master control means are in "lower" conditions.

4. A motor control system, comprising a multi-speed alternating-current motor having a plurality of selectively energizable field terminal groups for correspondingly different operating speeds, circuit means for supplying energy to said motor, a plurality of contactors having respective contact devices for selectively connecting said terminal groups to said circuit means and having respective coil circuits for closing when energized said respective contact devices so that the motor speed is determined by the one contactor coil circuit energized at a time, an operator-actuable master-controller connected to said coil circuits for sequentially energizing them one at a time, relay means comprising a timing relay of substantially instantaneous pick-up and delayed dropout performance and being connected with two of said contactors for controlling their respective coil circuits so that when said master controller is actuated to successively energize the coil circuits of said two contactors the minimum time elapsing between the successive energizing moments of said two respective contactor coil circuits is determined by the delay period of said relay drop-out performance regardless of whether said master controller is actuated in the accelerating or decelerating direction.

5. A motor control system, comprising a multi-speed alternating-current motor having a plurality of selectively energizable field terminal groups for correspondingly different operating speeds, circuit means for supplying energy to said motor, a plurality of contactors having respective contact devices for selectively connecting said terminal groups to said circuit means and having respective coil circuits for closing when energized said respective contact devices so that the motor speed is determined by the one contactor coil circuit energized at a time, an operator-actuable master controller connected to said coil circuits for sequentially energizing them one at a time, a

timing relay having a coil circuit and a contact device and being of the type having substantially instantaneous pick-up and delayed drop-out performance, said relay coil circuit being electrically interlocked with one of said contactors so that said relay is picked up only when the coil circuit of said one contactor is deenergized, and circuit means controlled by said relay contact device and connected to the coil circuit of said one contactor and to the coil circuit of another one of said contactors so that, when said master controller is actuated to successively energize the coil circuits of said latter two contactors, said timing relay picks up before the energization of the first energized contactor coil circuit and drops out before the energization of the subsequently energized contactor coil circuit, whereby the minimum time elapsing between the successive energizing moments of said two respective contactor coil circuits is determined by the delay period of said relay drop-out performance regardless of whether said master controller is actuated in the accelerating or decelerating direction.

6. A motor control system, comprising a multi-speed alternating-current motor having a plurality of selectively energizable field terminal groups for correspondingly different operating speeds, circuit means for supplying energy to said motor, a plurality of contactors having respective contact devices for selectively connecting said terminal groups to said circuit means and having respective coil circuits for closing when energized said respective contact devices so that the motor speed is determined by the one contactor coil circuit energized at a time, an operator-actuable master controller connected to said coil circuits for sequentially energizing them one at a time, a timing relay of substantially instantaneous pick-up and delayed drop-out performance having a coil circuit and contact means, said relay coil circuit being interlocked with one of said contactors so as to be energized only when the coil circuit of said one contactor is deenergized, a control relay having a coil circuit which is controlled by said contact means and extends through said master controller so as to be energized when said timing relay is dropped out while said master controller is in position to energize the coil circuit of another one of said contactors, said control relay having a normally open self-holding contact connected across said contact means and having a normally closed interlock contact disposed in the coil circuit of said one contactor and a normally open interlock contact disposed in the coil circuit of said other contactor, whereby the minimum time elapsing between the successive energizing moments of said two respective contactor coil circuits is determined by the delay period of said relay drop-out performance regardless of whether said master controller is actuated in the accelerating or decelerating direction.

7. A motor control system, comprising an alternating-current motor having four terminal groups for operating at four different respective speeds, line terminals, four speed-controlling contactors having respective contact devices for selectively connecting said terminal groups to said line terminals and having respective coil circuits for closing when energized said respective contact devices, a master controller connected to said coil circuits for sequentially energizing them one at a time, a first timing relay and a second timing relay both having sub-

stantially instantaneous pick-up and delayed drop-out performance, the delay period of said first timing relay being longer than that of said second timing relay and each timing relay having a coil circuit and contact means the coil circuit of said first timing relay being interlocked with the contactor for lowest motor speed so as to be energized when the coil circuit of said contactor is energized, a first control relay having a coil circuit controlled by said contact means of said first timing relay so as to be energized when said first timing relay is dropped out and having contact means connected in the coil circuit of another one of said contactors for a higher motor speed to permit energization of said latter coil circuit through said master controller only after said first timing relay has dropped out, the coil circuit of said second timing relay being interlocked with said latter contactor so as to be energized only when said latter coil circuit is deenergized, a second control relay having a coil circuit which is controlled by said contact means of said second timing relay and extends through said master controller so as to be energized when said second timing relay is dropped out while said master controller is in position to energize the coil circuit of a third one of said contactors for a still higher motor speed, said second control relay having a normally open self-holding contact connected across said contact means of said second timing relay and having a normally closed interlock contact disposed in the coil circuit of said second contactor and a normally open interlock contact disposed in the coil circuit of said third contactor.

8. A motor control system, comprising an alternating-current motor having terminal groups for operating at different respective speeds, line terminals, speed-controlling contactors having respective contact devices for selectively connecting said terminal groups to said line terminals, control means including a selectively operable master controller and being connected to said contactors for sequentially closing them one at a time in order to thereby control the motor speed, a load-responsive relay having contact means and a control coil, said coil being connected between one of said terminal groups for a high motor speed and the contactor appertaining to said one group so that said coil is energized to actuate said contact means when the current flowing through the motor at said higher motor speed exceeds a given value, said contact means being associated with said control means so as to open said one contactor and close another one of said contactors for a lower motor speed when said contact means are actuated by said coil, and timing means connected with said load-responsive relay so as to maintain said contact means ineffective a given interval of time after the closing of said one contactor.

9. A motor control system, comprising an alternating-current motor having terminal groups for operating at different respective speeds, line terminals, speed-controlling contactors having respective contact devices for selectively connecting said terminal groups to said line terminals and having respective coil circuits for closing when energized said respective contact devices, a master controller connected to said coil circuits for sequentially energizing them one at a time, a control relay having a normally closed contact series-disposed in the coil circuit

of the one contactor for highest motor speed, said control relay having a control coil and a normally open self-holding contact series-connected with each other and connected to said master controller so that said coil is energizable when said master controller is set for highest motor speed, a load-responsive relay having a coil connected between the one terminal group and the appertaining contactor for highest motor speed to be energized by motor current flowing when said motor is set to run at said highest speed, said load-responsive relay having a normally open contact controlled by said latter coil to close when said current exceeds a given value, a timing relay having a coil circuit interlocked with said one contactor for highest motor

speed so as to drop out upon elapse of a timing period after said one contactor has closed, said timing relay having a normally closed contact series-connected with said normally open contact of said load-responsive relay across said self-holding contact whereby said control relay causes opening of said one contactor when said load-responsive relay responds to excessive current after elapse of said timing interval, and circuit means linking said one contactor with the one other contactor for the next lower motor speed so as to cause closing of said other contactor when said one contactor is opened due to excessive current.
